UNITED STATES PATENT OFFICE.

VICTOR F. VON LOSSBERG, OF NEW YORK, N. Y., ASSIGNOR TO GILBERT AND BARKER MANUFACTURING COMPANY, OF SPRINGFIELD, MASSACHUSETTS, A CORPORATION OF MASSACHUSETTS.

DESIGN FOR AN INCANDESCENT GAS-BURNER.

No. 37,880.

Specification for Design.

Patented March 6, 1906.

Application filed January 3, 1906. Serial No. 294,476. Term of patent 14 years.

To all whom it may concern:

Be it known that I, VICTOR F. VON LOSSBERG, a citizen of the United States, residing in the city of New York, in the county and State of New York, have invented a new, original, and ornamental Design for Incandescent Gas-Burners, of which the following is a specification, reference being had to the accompanying drawing, forming a part hereof.

The drawing is a perspective view of an incandescent gas-burner, showing my new design.

I claim—

The ornamental design for an incandescent gas-burner, as shown.

VICTOR F. VON LOSSBERG.
